F. G. STUART

ATTACHMENT FOR ROTARY CLIPPER MACHINES

Filed April 2, 1921

Inventor
Fred. G. Stuart

By Lester L. Sargent

Attorney

UNITED STATES PATENT OFFICE.

FREDRICK GORDON STUART, OF WASHINGTON, DISTRICT OF COLUMBIA.

ATTACHMENT FOR ROTARY CLIPPER MACHINES.

Application filed April 2, 1921. Serial No. 458,154.

To all whom it may concern:

Be it known that I, FREDRICK GORDON STUART, a citizen of the United States, and residing at Washington, District of Columbia, have invented a new and useful Attachment 5 for a Rotary Clipping Machine, of which the following is a specification.

The object of my invention is to provide an attachment which will be readily applied 10 to any of the rotary clipper machines now on the market, which will make it possible to use such machines for the purpose of operating a buffing or grinding wheel, whereby to double the usefulness of such machines. 15 It is further an object of my invention to provide a device of this character of relatively simple construction.

The accompanying drawing is a vertical section through the device, with a buffing 20 wheel which is designed to be attached to it, shown in dotted lines.

Referring to the drawing, 1 designates the usual flexible chain of the rotary clipper machine; having the usual flexible tube or 25 cover 2 and chain 1 having a hook 4 attached to the revolvable head 5 which I have provided and which is mounted in a suitable casing 6 having a tapered shank which is releasably secured in the conventional steel 30 collar or holder 3 of the rotary clipper machine. I provide suitable ball bearings 9 for the revolvable head 5. I further provide a suitable oil channel 10 in head 6. I 35 may also provide an oil channel 10^a in member 6, but this oil channel is optional and preferably may be omitted. I provide a suitable collar 7 secured to the threaded portion 40 of the bearing 6, and including a chambered inner portion for the reception of the lower set of ball bearings 9 as illustrated. I further provide a threaded opening 45 11 extending longitudinally inward from the end of revolvable head 5 and adapted to receive a suitable screw 12 which extends through washers 13 and buffing wheel 14 for the purpose of releasably securing the buffing wheel to the end of the revolvable head 5, the end 15 of which projects beyond the end of the nut or collar 7.

50 In operating the device members 7, 6 and 5, attached to each other, are inserted in the conventional steel collar of the rotary clip-

per machine, and the hook 4 of the flexible chain of the rotary clipper is attached to the end of the revolvable head 5. The buffing wheel 14 is thus secured to the outer end 55 15 of the revolvable head by the screw 12 which engages in the correspondingly threaded channel 11 in head 5. An emery or buffing wheel can thus be readily applied 60 to standard rotary clipper machines so that the owner of one of these machines may have the advantage of a buffing device as well as a clipping device. The revolvable head 5 is suited for attachment of any desired emery 65 wheel or buffing wheel, permitting utilization of the device for sharpening such devices as mowing machine knives without the inconvenience of removing them from their mounting; and for other purposes for which 70 this attachment is applicable.

What I claim is—

1. An attachment for a rotary clipper machine, comprising a revolvable head engageable to the end of the flexible rotating chain 75 of the clipper machine, a casing member and bearing for the revolvable head, said casing member being of frusto-conical shape and slidably detachable from and frictionally engageable on the collar of the rotary clipper 80 machine, a collar secured to the end of the casing, the revolvable head projecting slightly beyond said cap, and means for attaching a suitable operating member such as a buffing wheel to the end of the revolvable 85 head.

2. In an attachment for a rotary clipper machine, the combination of a revolvable head releasably attachable to the flexible rotating chain of a rotary clipper machine, a casing member for said revolvable head, said casing member having a tapered shank frictionally engageable on and releasably attachable to the collar of the rotary clipper machine, the revolvable head being provided 90 with an enlarged section and the casing with a recessed section to provide bearing portions, ball bearings interposed therebetween, an end collar releasably attached to the casing and securing the revolvable head 95 within the casing, and means for securing a buffing wheel or similar device to the outer end of the revolvable head.

FREDRICK GORDON STUART.
